(57) **CLAIM**

The ornamental design for a game console stand, as shown and described.

DESCRIPTION

FIG. 1 is a front, right and top perspective view of a game console stand showing my new design;

FIG. 2 is a rear, left and top rear perspective view thereof;

FIG. 3 is a rear, left and bottom perspective view thereof;

FIG. 4 is a front view thereof;

FIG. 5 is a rear view thereof;

FIG. 6 is a left view thereof;

FIG. 7 is a right view thereof;

FIG. 8 is a top view thereof; and,

FIG. 9 is a bottom view thereof.

The broken lines shown in the figures are for the purpose of illustrating portions of the game console stand, which form no parts of the claimed design.

1 Claim, 9 Drawing Sheets
